CLAIM

The ornamental design for a clamshell container for food items, as shown and described.

DESCRIPTION

FIG. 1 is a perspective view of a clamshell package for food items showing our new design;

FIG. 2 is a right side elevational view thereof; the left side elevational being a mirror image thereof;

FIG. 3 is a front elevational view thereof;

FIG. 4 is a rear elevational view thereof;

FIG. 5 is a bottom plan view thereof; and,

FIG. 6 is a top plan view thereof.
